UNITED STATES PATENT OFFICE.

THOMAS HOMER FULLER, OF LAFAYETTE, ALABAMA.

PLOW.

No. 884,652.

Specification of Letters Patent.

Patented April 14, 1908.

Application filed July 12, 1907. Serial No. 383,470.

To all whom it may concern:

Be it known that I, THOMAS HOMER FULLER, a citizen of the United States, residing at Lafayette, in the county of Chambers and 5 State of Alabama, have invented certain new and useful Improvements in Plows; and I do hereby declare the following to be a full, clear, and exact description of the invention, such as will enable others skilled in the art 10 to which it appertains to make and use same, reference being had to the accompanying drawings, and to the letters and figures of reference marked thereon, which form a part of this specification.

15 This invention relates to new and useful improvements in plows and the object of the invention is to produce a device of this nature and so constructed that the parts which are subjected to the greatest wear will be reinforced.

20 The invention consists of various details of construction and combinations and arrangements of parts which will be hereinafter fully described and then specifically defined in the appended claim.

25 I illustrate my invention in the accompanying drawings, in which:

Figure 1 is a perspective view of the plow. Fig. 2 is a similar view of a modification, and 30 Fig. 3 is a cross sectional view through the form shown in Fig. 1.

Reference now being had to the details of the drawings, by letter, A in Fig. 1 designates a bias point scooter plow having an aperture 35 B therein for the reception of a heel bolt.

Said plow is made preferably of steel of a thickness of substantially $\frac{3}{16}$ of an inch with its opposite edges D turned at an angle downwardly forming wings or flanges, thereby offering a more substantial and thicker 40 portion of the plow where the greatest wear comes.

In Fig. 2, I have shown a modification of the plow in which the aperture B is adjacent to one edge thereof, and, in Fig. 3 of the 45 drawings, I have shown the application of my invention to a bull tongue scooter plow in which the thickness of the plow gradually increases toward the center where it is formed into a ridge and through which an 50 aperture E extends for the reception of a heel bolt. In each of the forms shown, the same principle of my invention obtains, that is to say the formation of the plow with reinforced or thickened edges where the most wear 55 comes upon it.

What I claim to be new is:—

A plow having converging wings upon the opposite longitudinal edges thereof, the surface of the plow intermediate said wings 60 being concaved and its opposite face convexed, the forward end of the plow tapering to a point which is at one side of the longitudinal center of the plow, as set forth.

In testimony whereof I hereunto affix my 65 signature in the presence of two witnesses.

THOS. HOMER FULLER.
